UNITED STATES PATENT OFFICE.

JOHN F. KOCH, OF STEELTON, PENNSYLVANIA.

VEHICLE-TOBOGGAN.

SPECIFICATION forming part of Letters Patent No. 371,770, dated October 18, 1887.

Application filed August 5, 1887. Serial No. 246,185. (No model.)

To all whom it may concern:

Be it known that I, JOHN F. KOCH, a citizen of the United States, and a resident of Steelton, in the county of Dauphin and State 5 of Pennsylvania, have invented certain new and useful Improvements in Vehicle-Toboggans; and I do hereby declare that the following is a full, clear, and exact description of the invention, which will enable others skilled in 10 the art to which it appertains to make and use the same, reference being had to the accompanying drawings, which form a part of this specification, and in which—

Figure 1 is a perspective view of my improved vehicle-toboggan, showing the same in 15 position on the double rails on which it is adapted to run. Fig. 2 is a side elevation of my improved vehicle-toboggan with one of the wheels removed. Fig. 3 is a top plan view 20 of the toboggan, and Fig. 4 is a perspective detail view taken from the lower or under side of the vehicle-toboggan.

The same letters of reference indicate corresponding parts in all the figures.

25 My invention consists in a new and improved vehicle-toboggan, which will be hereinafter fully described and claimed.

Referring to the several parts by letter, A indicates the foot-board or bottom of my new 30 and improved vehicle-toboggan, which is supported on the axles B B, having mounted on their outer ends or spindles, B' B', the supporting-wheels C. These wheels C are formed at their peripheries with the central flange, C', 35 forming on each side thereof the tread C' C', as shown, and the inclined way down which the toboggan runs is provided with the double rails D D, or with a single rail having a deep central groove, between which rails D D, or 40 in the central groove of the single, fit and run the central flanges, C, of the four wheels C, while the flat treads C' on both sides of the said central flanges rest and bear upon the flattops 45 of the rails D, as shown in the perspective view, Fig. 1, of the drawings.

To the lower side of the foot-board A are secured longitudinally at each edge thereof the flat metal braces or bars E E, the ends of these flat braces being secured between the 50 axles and the under side of the foot-board, the axles B being slightly recessed at the points

where they cross or extend under the said braces, the brace bars fitting in the said recesses.

Upon the rear part or end of the foot-board 55 over the rear axle is secured the rear seat, F, the front and rear ends of which are supported on and by the solid end supports G G, as shown, the said supports being reduced slightly toward their lower ends, where they are secured upon the foot-board, while the sides of the seat are supported by the side braces H, consisting each of a main or body piece, I, which is bent into a substantially U shape, with its flattened lower end resting in a recess, 65 J, in the edge of the foot-board immediately over the axle, so that the lower flat middle portion of the brace rests upon and is bolted to the flat brace-bar E at that point, as clearly shown in the side elevation, Fig. 2, of the 70 drawings, while the sides of this lower section I of the brace extend upward like the sides of a letter V, and have their upper ends bent outward horizontally, the top of the brace being formed by a flat horizontal metal bar, K, 75 the ends of which are bolted to the ends of the lower section I, the ends of this flat bar K and of the part I being bolted to the lower side of the seat, the flat top bar, K, of the brace resting flat against the bottom of the 80 seat toward the outer side edge of the same.

F' indicates the front seat, which is arranged immediately over the front axle, being supported at its front and rear ends upon solid braces or end supports G' G', and having its 85 sides supported by side braces H', precisely similar in construction to the side braces H of the rear seat, the lower central portions of the lower or main sections I' of these side braces resting in edge recesses, J', in the foot-board, 90 so that their flat central parts rest upon and are bolted to the flat brace-bars E E at those points immediately above the front axle. The solid end supports G' G' of the front seat are similar in construction to those of the rear 95 seat, being reduced in size toward their lower ends, where they are secured upon the foot-board.

Both the front and back seat are provided with the low outwardly-inclined railings M M, 100 which extend around three sides of the seats, as shown, leaving the front side of the seats,

of course, open; and the seats may be, and are, preferably, cushioned with a suitable cushion, N, which may be covered with plush or the like to present an ornamental appearance.

5 The foot-board is provided at its front end, in front of the forward seat, with a foot-rest, O, against which the feet of the person in the foremost seat are pressed or braced to steady the rider.

10 A curved guard, P, is secured over and slightly in front of each of the four wheels to protect the clothes or dress of the person riding in the toboggan from dirt and dust.

15 In operation it will be seen that the deep central flanges of the four wheels fitting in the deep grooves of the rails, or between the flat double rails when such are employed, will effectually prevent the possibility of the vehicle-toboggan swerving to either side, and so 20 running off over the edge of the inclined way down which the toboggan travels, this improved construction of the wheels being a safeguard against and effectually preventing the only serious accident to which this species of 25 tobogganing has been liable—namely, the danger of the toboggan swerving to one side, and thus running off over the edge of the high elevated inclined way down which it travels.

30 Besides the deep flanges resting between the double rails, or in the deep central groove of a grooved rail, the flat wide treads on each side of the said central flanges also operate materially to steady the toboggan while in movement and cause it to run straight and 35 evenly.

35 From the foregoing description, taken in connection with the accompanying drawings, the construction, operation, and many advantages of my invention will be readily seen and 40 understood.

45 It will be seen that my improved vehicle-toboggan is simple, light, and strong in construction, convenient and comfortable to ride in, and exceedingly safe and efficient in operation.

45 The improved wheels greatly lessen the danger attendant on the sport, while the construction of the several parts, particularly the construction and arrangement of the braces E and H, render the machine peculiarly strong 50 in proportion to its size and weight.

It will be seen that my improved vehicle-toboggan forms an exceedingly convenient, comfortable, light, and strong machine. The guards or shields P protect the clothes of the rider from becoming soiled while riding on the 55 toboggan, and thus add to its neatness and comfort. The wheels may be retained on the ends of the axles by means of pins or split keys passing through apertures in the ends of the axles, but are preferably retained by means 60 of the screw-caps Q, which screw upon the threaded ends of the axles.

Having thus described my invention, what I claim, and desire to secure by Letters Patent of the United States, is—

1. The combination, with the foot-board having the edge slots or openings, of the flat longitudinal edge braces, the seats, and the side braces formed of the bent lower body portions and the flat top pieces, substantially as 70 set forth.

2. The combination, with the foot-board, of the flat longitudinal edge braces, the axles, the supporting-wheels, the seats having the end supports and the side braces and provided 75 with the side and back rails, the foot-rest secured upon the front end of the foot-board, and the curved guards arranged as described, substantially as and for the purpose herein set forth.

3. The combination, with the double or grooved rails, of the vehicle-toboggan consisting of the foot-board having the edge slots or openings, the axles, the wheels formed with the central annular wide flanges, the flat longitudinal brace-bars, the seats, the end supports, the side braces consisting of the bent lower body portions and the flat top pieces, and the foot-rest secured upon the forward end of the foot-board, all substantially as and for 85 90 the purpose herein set forth.

In testimony that I claim the foregoing as my own I have hereunto affixed my signature in presence of two witnesses.

JOHN F. KOCH.
